United States Patent

Des. 241,825
Patented Oct. 12, 1976

241,825

ALARM CABINET

J. Budd Steinhilber, Mill Valley, Calif., assignor to
Optical Coating Laboratory, Inc.

Filed Dec. 12, 1975, Ser. No. 640,033

Term of patent 14 years

Int. Cl. D10—05

U.S. Cl. D10—106

FIG. 1

FIG. 4

FIG. 5

FIG. 2

FIG. 3

FIG. 6

FIG. 1 is a left front perspective view of an alarm cabinet showing my new design;

FIG. 2 is a top plan view thereof;

FIG. 3 is a front elevational view thereof;

FIG. 4 is a right side elevational view thereof, the left side being a mirror image thereto;

FIG. 5 is a bottom plan view thereof; and

FIG. 6 is a rear elevational view thereof.

I claim:

The ornamental design for an alarm cabinet, as shown and described.
